(57) **CLAIM**

I claim the ornamental design for a microphone, as shown and described.

DESCRIPTION

FIG. 1 is a tilted, perspective view of a microphone, showing my new design.

FIG. 2 is a straight, perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

Broken lines are for illustrating portions of the microphone which form no part of the claimed design.
